CLAIM

The ornamental design for a multi-collar finish for a wine bottle, as shown and described.

DESCRIPTION

FIG. 1 is a perspective view from above of the multi-collar finish for a wine bottle invention;

FIG. 2 is a perspective view from below of the invention;

FIG. 3 is a front elevation view of the invention, the rear elevation view being a mirror image;

FIG. 4 is a right side elevation view of the invention, the left side elevation view being a mirror image;

FIG. 5 is a top plan view of the invention;

FIG. 6 is a bottom plan view of the invention;

FIG. 7 is a cross-section view of the invention, taken along and in the direction of line 7-7 in FIG. 6; and,

FIG. 8 is a cross-section view of the invention, taken along and in the direction of line 8-8 in FIG. 6.

The broken lines represent environmental structure and form no part of the claim.

1 Claim, 4 Drawing Sheets
